ABRADING APPARATUS

Walter L. Keefer, Hagerstown, Md., assignor to
 Pangborn Corporation, Hagerstown, Md., a
 corporation of Maryland

Application September 2, 1937, Serial No. 162,214

26 Claims.

(Cl. 51—9)

The present invention relates to abrading apparatus, and more particularly to apparatus known in the trade as blast cleaning machines embodying means for projecting a stream of abrasive in the form of sand or steel abrasive against castings or other articles of work to be cleaned of surface accumulations.

Although centrifugal abrading machines have been known for years in the abrading art, both with directional control and without directional control, the problem of wear of the blades and other parts has been a serious consideration, regardless of whether they are of the "slider" type, wherein the abrasive is admitted at low velocity over the inner ends of the blades and is continuously accelerated to the blade tips or whether they are wheels embodying batter blades where the entire abrading velocity is imparted to the abrasive by a single instantaneous impact therewith.

Although the slider type machines in commercial use today represent a great advance in the art over the machines heretofore in use they do not possess all of the operating characteristics desired and fall considerably short of the "ideal" machine which would pick the abrasive up without shock and gradually move it out to the periphery of the rotor without sliding it and then discharge it without wearing influence upon any part of the machine.

It is accordingly a primary object of this invention to provide an abrasive throwing wheel which does not employ any blades whatsoever and more nearly approaches the "ideal" abrading apparatus than anything heretofore proposed.

It is another object to devise a centrifugal abrading machine wherein the abrasive is admitted near the axis of rotation, moves outwardly with substantially no propelling influence and then is released from the wheel substantially at the peripheral speed thereof without having a battering or other impacting action applied thereto.

It is a further important object to design a wheel for mechanically throwing abrasive which employs no blades whatsoever, retains a predetermined quantity of abrasive in the wheel at all times and discharges a predetermined quantity at each rotation of the wheel and imparts a high abrading velocity to the abrasive.

My invention also aims to provide an abrasive and feeding and propelling assembly that may be used in combination with centrifugal bladed rotors for imparting directional control thereto.

Further objects of the invention will become apparent as the accompanying specification pro-

ceeds in connection with the annexed drawings and from the appended claims.

In the drawings:

Figure 1 is a longitudinal sectional view of an apparatus embodying the invention.

Figure 2 is a view looking from the right hand side of the machine shown in Figure 1 and parts have been broken away in order to more clearly show the structure involved.

Figure 3 is a sectional view taken on the line 3—3 of Figure 2 showing the parts as they appear when viewed in the direction of the arrows.

Figure 4 is a fragmental sectional view of a part of wheel shown in Figure 1 and illustrates one of the abrasive discharge openings.

Figure 5 is an elevational view of the feed chamber of the machine of Figure 1, and illustrates the abrasive deflector.

Figure 6 is a longitudinal sectional view similar to Figure 1 but illustrates a modified form of the invention.

Figure 7 is an elevational view looking from the right hand side of Figure 6 and parts have been broken away in order to more clearly show the structure involved.

Figure 8 is a fragmental sectional view of the machine shown in Figures 6 and 7 and illustrates the rotatable disc employed to deflect or dislodge the abrasive from the inner surface of the wheel.

Figure 9 is a longitudinal sectional view through a further modified form of wheel also forming part of the invention.

Figure 10 is a partial elevational view of the machine shown in Figure 9 and illustrates it as it appears when viewed from the right hand side of that figure.

Figure 11 is a fragmental partial sectional view of machine shown in Figures 9 and 10 and shows the deflecting members.

Figure 12 is a face view of a bladed rotor embodying the abrasive propelling mechanism of the invention.

Figure 13 is a longitudinal sectional view through the wheel shown in Figure 12, and in this form the deflecting disc has been only diagrammatically illustrated.

Figure 14 is an enlarged sectional view of the feeding mechanism employed in the machine of Figures 12 and 13 and illustrates the manner in which the abrasive is introduced into the abrasive chamber and discharged therefrom.

With continued reference to the drawings, wherein like reference characters have been employed throughout the several views thereof to

designate like parts, and with particular reference to Figures 1 to 5, inclusive, the machine broadly comprises a hollow rotatable member upon whose inner surface the abrasive is centrifugally built up and the layer of abrasive is automatically discharged from the member at a predetermined point in rotation by means of a deflector which directly engages the layer of abrasive deposited within said member.

- 10 The hollow member just referred to includes a head 10, which is mounted on a shaft 11. The latter is journaled for rotation in any suitable manner. As seen in Figure 1, head 10 is hollowed out from one side and is provided with an 15 abrasive accelerating groove 12 at its periphery which merges with a radial face 13 of the rotor. Head 10 is also provided with a flanged portion 14 in which a plurality of abrasive discharge openings 15 are provided.

In order to provide for wear of the parts and make it possible to replace certain parts of the machine without replacing the entire rotor, a wear bushing 17 is disposed in each opening 15 and as seen in Figures 1 and 4, each wear bushing 17 is provided with a portion extending into opening 15 and is provided with an inclined rear wall 18 for a purpose that will presently appear.

A disc 21 is preferably secured to the end of the rotor for preventing inadvertent escape of 30 abrasive, but it may be omitted if desired.

The abrasive may be admitted to the interior of the rotor in any suitable manner, but I preferably employ a generally cone shaped member 22 having a funnel portion 23 and which is 35 mounted on a shaft 24. Shaft 24 is journaled in a bearing 25 provided on a bracket 26 and the latter is secured to a stationary base 27.

Feed chamber 22 is accordingly mounted for rocking movement about the axis of rotation of 40 the rotor and it is provided with a handle 28 for manipulating it into its adjusted position. A set screw 29 is threaded into bracket 26 for locking shaft 24 in its proper adjusted position.

Assuming that shaft 11 is driven by any suitable prime mover at a speed of approximately 45 2500 revolutions per minute, and abrasive is admitted to spout 23, it will travel at relatively low velocity until it strikes the mass of abrasive in the abrasive acceleration groove 12, where it will be picked up and rapidly attain the peripheral 50 speed of the rotor. In view of the fact that when the wheel is in operation groove 12 is filled with abrasive, the accelerating action imparted to the abrasive is taken by the abrasive itself that is accumulated in the groove, and accordingly wear of the acceleration groove walls is minimized.

Assuming that the wheel is rotating as just described, the abrasive will fill up groove 12 and then spill over onto the internal surface 31 of the rotor. The parts are so designed, and rotor surface 31 is of sufficient width so that as the abrasive builds up it will assume the form of a cone with its inner surface inclined at an angle equal to the angle of repose of the particular 65 abrasive, and during normal operation will not spill into openings 15 unless it is acted upon by the deflector, which will now be described.

One form of deflector means that may be used to dislodge abrasive at a predetermined point in 70 the revolution of the rotor, is shown in Figures 3 and 5, and it consists of a comparatively thin blade 33 made from any suitable heat resistant material, such as tungsten alloy steel.

Deflector blade 33 may be stationarily supported in any desired manner but in the present

instance I have shown it as being supported by a pair of bosses 34 on member 22 by means of a pair of screws 35.

Deflector 33 is curved as seen in Figure 2, and its outer edge lies in close proximity to the inner surface of the rotor, with the result that when the wheel is rotated the layer of abrasive lying on surface 31 will be continuously acted upon by the deflector and deflected into openings 15.

Referring to Figure 3, with the wheel rotating in the direction indicated by the arrow, an abrasive particle is indicated at 38 as just contacting blade 33. This particle, prior to engagement thereof with the deflector possessed a velocity 15 V_r or a velocity equal to the peripheral speed of the rotor.

Upon engagement of the particle with deflector 33, it assumes a velocity having an axial component V_d and the two combined give a resultant 20 velocity V_x . Therefore, there is continuously deposited on the inner surface 31 a layer of abrasive and this layer of abrasive is being continuously discharged from the wheel at one point by reason of deflector 33 engaging it and causing it to be pushed axially into registry with the discharge openings.

In view of the fact that the abrasive lying centrifugally on surface 31 is rotating at the peripheral speed of the wheel, and as this speed 30 is selected to correspond to the desired abrasive discharge speed, it is unnecessary to impart a blade action upon the abrasive as it is spilled through opening 15 in order to impart an abrading velocity thereto. Wall 18 of opening 15 is 35 accordingly inclined as shown in Figure 4 in order to avoid an impelling influence being given to the abrasive as it passes through opening 15. However, if desired, the combination of the rim discharge and blade action may be used, and in 40 a succeeding form of the invention I have shown a machine of just this character.

In view of the fact that the point of discharge of the abrasive is dependent upon the angular position of deflector 33, the wheel may be caused 45 to fire in any direction by loosening screw 29 and rocking the feed chamber 22 in the proper direction to cause the machine to discharge in the desired direction. As a matter of fact, if it is desired to have the machine discharge upwardly 50 the feed chamber may be located in the position shown in the drawings, but the deflector may be secured thereto at a point 180 degrees removed from the location shown in order to make the wheel fire upwardly rather than downwardly. If 55 after the wheel is in use it is found that the spray angle or the width of the centrifugal blast is too narrow, the deflector may be moved closer to the wheel so as to deflect a greater depth of abrasive for each revolution, or the deflector may 60 be longer so as to deflect a greater body of abrasive or a flange may be provided on the deflector to dislodge a greater quantity of abrasive. To this end member 33 may be adjustably mounted on chamber 22 or any other stationary 65 part of the machine.

If desired, however, two deflectors may be placed in series at different angular points so as to increase the width of the abrasive spray angle.

Although I have shown a particular feed chamber for introducing the abrasive in the rotor, it is to be understood that if desired various other forms of abrasive admitting means may be used. For instance, abrasive may be admitted at the center of a pair of grooved rotating discs and be 75

allowed to trickle outwardly thereover and gradually accelerated.

Taking up the form of invention illustrated in Figures 6, 7 and 8, the major differences between this device and the first described form of the invention reside in the use of a wheel having passages for gradually accelerating abrasive as it moves outwardly and also, a rotatable disc which is employed to deflect the abrasive at a predetermined point in rotation. In this form of the invention a rotor 40 is mounted on shaft 41 and is provided with a pair of abrasive accelerating flanges 42 and 43, an abrasive acceleration groove 44 and an abrasive supporting or deposit surface 45.

In this form of the invention feed chamber 46 is similar to that previously described with the exception that it provides a pair of annular grooves 47 and 48 which cooperate with flanges 42 and 43 of rotor 40 to define a tortuous passage. Therefore when the abrasive introduced in chamber 46 first encounters flange 42 it is partially accelerated, fills up to the angle of repose and spills off the edge into groove 47 where it is deflected onto flange 43. Flange 43 being further from the axis of rotation is rotating at a greater peripheral speed than flange 42, the abrasive accordingly receives further acceleration when it strikes this flange. The abrasive then spills off flange 43 into the acceleration groove, which, being located still further from the axis of rotation further accelerates the abrasive.

The feed chamber is mounted on a shaft 49 as before, which is journaled in a bracket 51 carried by a base 52. An operating handle 53 is employed to rock the feed chamber into the proper angular position and the set screw 54 is employed to lock it in place.

In this form of the invention a disc 56 cooperates with the rotor to spill the abrasive over the side edge of the rotor and it is journaled in a bearing 57 carried by an arm 58 which, as shown, is an integral part of the feed chamber, with the result that the direction of discharge may be controlled by rocking the feed chamber. Although wheel 56 may if desired be driven by a separate prime mover, it has been found that the friction of the abrasive upon the wheel is sufficient to cause it to undergo independent rotation. Disc 56 may also, if desired, be adjustably supported so as to dispose its axis at any suitable inclination to the axis of the wheel.

By reason of the fact that the peripheral speed of disc 56 is substantially equal to the peripheral speed of rotor 40, it is apparent that it will undergo a minimum abrading action during operation, and at the same time smoothly spills the abrasive over the side or discharge edge 59 of the rotor.

Although I have illustrated disc 56 as lying at a predetermined angle with respect to the axis of rotation of rotor 40, it is to be understood that this angle may be increased or the disc axis inclined so as to dispose the disc in other directions for discharging the abrasive from the wheel, depending upon the particular work being handled, the abrasive used, and other influential factors.

It is accordingly seen that with this form of the invention the abrasive continuously spills over the edge 59 of rotor 40 in a smooth unbroken stream of narrow width, whereas in the first form of invention described, the abrasive discharge is discontinuous in the sense that it is successively discharged through openings 15. If desired sur-

face 45 and/or edge 59 may be formed in a separate removable and replaceable wear element.

It will be understood that a disc deflector like that used in the form of the invention illustrated in Figures 6, 7 and 8 may be used instead of the deflector 33 in the form of the invention illustrated in Figures 1, 2 and 3.

Referring now to Figures 9 and 10 of the drawings, I have shown a wheel somewhat similar to the wheels previously described and embodying a rotor 60 mounted on a shaft 61 and having a rim portion 62 to which is secured an end plate 63. In rim portion 62 there are provided a plurality of inserts 64 affording a plurality of discharge openings 65.

In this form of the invention no acceleration groove is employed as the abrasive is dumped into a recess 66 provided in the rotor disc and builds up on surface 67 where it is deflected into discharge opening 65 by either a stationary deflector member or a rotatable disc as described in connection with the first form of the invention.

In this form of the invention a cage is employed embodying a cone portion 68 which is secured to a hub portion 71 by a plurality of cap screws 72. Portion 71 is provided with a funnel portion 73 and it is secured to a hollow shaft 74 by means of a key 75 and a set screw 76. Shaft 74 is journaled in a support 78 and is provided with an operating handle 79. Shaft 74 is adjustably locked in fixed position by nut and bolt assembly 81 which cooperates with an arcuate slot 82 in support 78, whereby the parts may be locked by tightening the nut and bolt assembly.

Journalized in sleeve 74 is a shaft 83 to which is secured a handle 84 by means of a set screw 85. Handle 84 carries a detent 86 which cooperates with serrations 87 formed on a downward extension 88 of handle 79. This device is similar to that described in connection with the first form of the invention, the abrasive being admitted in chamber 69 and piling up against the inner surface 67 of the rotor and being dislodged or deflected through opening 65 by means of a stationary supported deflector either of the stationary plough or shoe type shown in Figure 5 or the rotatable disc type shown in Figure 8. I have however, illustrated it as comprising a shoe 88 which is adjustably mounted on chamber 69 by a pair of stud and nut assemblies 89. Shoe 88 is inclined in a manner similar to shoe 33 of Figure 5 and it may be adjusted, either to vary the discharge of the machine or to compensate for wear by loosening the stud and nut assemblies.

In this form of the invention there is employed a primary deflector blade 90 which acts upon the abrasive before blade 88 comes into play and as the initial contact is of greatest magnitude the primary blade takes the most wear. Accordingly in order to make blade 90 quickly and easily adjustable to compensate for wear it is mounted for guided sliding movement in a recess in chamber 69 and projects outside chamber 69 adjacent the leading edge of blade 88.

Pivots secured to blade 90 by means of a pin 65 91 is a connecting link 92, which in turn is connected by means of a crank pin 93 to a disc 94 rigidly carried by shaft 83.

It is accordingly apparent that when the machine is placed in operation blade 90 will initially contact and apply a primary deflecting action upon the layer of abrasive accumulated on surface 67 and blade 88 will apply a secondary deflecting action thereupon. When the outer end of blade 90 has become worn through contact 75

of the abrasive therewith lever 84 may be rocked so as to cause link 92 to project blade 90 outwardly into a new position. The parts have been illustrated as "new" and hence in Figure 10 lever 84 may be moved step by step through 180° before blade 90 is unfit for further service. Also, from time to time blade 88 may be adjusted outwardly to compensate for wear in the manner previously described.

10 In Figures 12, 13 and 14, I have shown a combination of a rim discharge abrasive throwing wheel used as the feeder for a bladed abrasive throwing wheel.

With continued reference to these figures, a 15 rotor 110 mounted on a shaft 111 is provided with a plurality of abrasive propelling blades 112. The blades terminate short of the axis of revolution to define a central space and mounted in this space is a chamber 113 and it is preferably 20 removable so that it may be taken out and replaced when it has become too worn for further service.

The abrasive is fed to the interior of member 113 by means of a feed conduit 115. Journaled in conduit 115 or in any other suitable manner is a shaft 116, carrying a spider 117 which in turn supports a disc 119. In this form of the invention abrasive is introduced through chute 115 and piles up to its angle of repose on the 30 interior of member 113, and at a predetermined point in the rotation of the parts disc 119 deflects a layer of abrasive over the edge 121 of member 113 onto the inner ends or heels of the throwing blades. In view of the fact that the 35 direction of discharge of the abrasive from member 113 is substantially tangential the abrasive is picked up by the inner ends of the blades with negligible impact.

The direction of discharge from this wheel 40 may be controlled in a manner similar to that effected in the wheels previously described, namely, by adjusting angularly the point at which the deflector cooperates with the abrasive lying on the inner surface of member 113. Accordingly 45 it is only necessary to adjust spout 115 and shaft 116 to locate disc 119 in the proper position to effect the desired discharge of abrasive.

Although I have shown member 113 as being 50 driven synchronously with the rotor and feeding the abrasive over the inner ends of the blades, it may be independently driven and feed the abrasive over the side edges of the blades without departing from the spirit of my invention. Also, 55 I have illustrated certain parts of the apparatus as being integrally formed with the rotor, but it is to be understood that if desired separate replaceable wear elements may be provided.

In all of the forms of the invention the abrasive 60 is deposited on the inner surface of the rotor and builds up to its angle of repose and therefore the deflector need apply but force enough to cause the abrasive to move to the discharge point. Therefore, the wear on the deflector is minimized.

The invention may be embodied in other specific forms without departing from the spirit or 70 essential characteristics thereof. The present embodiment is therefore to be considered in all respects as illustrative and not restrictive, the scope of the invention being indicated by the appended claims rather than by the foregoing description, and all changes which come within 75 the meaning and range of equivalency of the

claims are therefore intended to be embraced therein.

What is claimed and desired to be secured by United States Letters Patent is:

1. In an abrading apparatus, a structure 5 mounted for rotation at high speed, said structure providing a generally annular surface facing toward the axis of rotation of said structure, means for depositing abrasive upon said surface, and discharge means for dislodging the 10 deposited abrasive from said surface at a predetermined point in the rotation of said structure for projecting said abrasive at an abrading velocity.

2. The abrading apparatus set forth in claim 1, 15 wherein said discharge means comprises a stationarily supported device for directly engaging the deposited abrasive and imparting an axial movement thereto.

3. The abrading apparatus set forth in claim 1, 20 wherein said discharge means comprises a stationarily supported device mounted adjacent said structure and cooperating with said deposited abrasive, said device being movable into a plurality of angular positions with respect to the 25 axis of said structure, whereby the direction of the discharge of abrasive from said structure may be varied at will.

4. In an abrading apparatus, a structure 30 mounted for rotation at high speed, said structure providing a generally cylindrical surface facing the axis of rotation of said structure, means for depositing abrasive upon said surface while said structure is rotating, and discharge means for moving said deposited abrasive axially so 35 as to discharge it from one edge of said surface when said abrasive attains a predetermined position in the rotation of said structure.

5. The abrading apparatus set forth in claim 4, 40 wherein said discharge means comprises an inclined deflector blade stationarily supported adjacent said structure and operable to engage and deflect said deposited abrasive axially over said one edge of said surface.

6. The abrading apparatus set forth in claim 4, 45 wherein said discharge means comprises a rotatable member disposed adjacent said structure and operable to directly engage said deposited abrasive.

7. In an abrading apparatus, a structure 50 mounted for rotation at high speed and comprising a hollow member, means for depositing abrasive upon the inner surface of said member while the latter is rotating and abrasive discharge means for engaging and deflecting said abrasive over one end of said member while the same is 55 rotating for discharging said abrasive at an abrading velocity.

8. The abrading apparatus set forth in claim 7, 60 wherein said first named means is operable to deposit abrasive upon said member at a point sufficiently remote from said one end of said member so that said abrasive will build up to its angle of repose adjacent to but short of said one end of said member, whereby said abrasive 65 will be discharged from said member only when it is engaged by said abrasive discharge means.

9. An abrading apparatus comprising a structure 70 mounted for rotation at high speed, said structure embodying a hollow member rotatable with said structure with its axes coincident to the axis of rotation of said structure, said member having a plurality of discharge openings provided therein disposed in the same general plane of revolution, means for depositing abrasive upon 75

the inner surface of said member in a region spaced from said discharge openings, and means located within said member for engaging the layer of abrasive deposited within said member and moving it axially to said discharge openings.

5 10. In an abrading apparatus, a structure mounted for rotation at high speed, said structure providing an annular inwardly facing abrasive supporting surface terminating at one end in an abrasive discharge edge, means for depositing abrasive upon said surface while said structure is rotating and allowing said abrasive to attain the full peripheral speed of said inner surface, said abrasive being deposited upon said inner surface at a point spaced from said discharge edge and adapted to build up thereon to its angle of repose without spilling over said discharge edge, and a rotatable disc mounted adjacent said structure for deflecting said deposited abrasive over said discharge edge and discharging it at an abrading velocity.

15 11. The abrading apparatus set forth in claim 10, wherein said structure is provided with an abrasive acceleration groove adjacent said annular surface which is adapted to accumulate a body of abrasive when said structure is rotating.

20 12. The abrading apparatus set forth in claim 10, wherein said structure is provided with means for accelerating the abrasive in stages before it is deposited upon said annular surface, whereby said abrasive promptly attains the full peripheral speed of said structure upon contact therewith.

25 13. In an abrading apparatus, a structure mounted for rotation at high speed and having a plurality of abrasive propelling blades provided thereon, and means mounted adjacent the center of rotation of said structure for feeding a stream of abrasive over the edges of said blades for causing the abrasive to be picked up and discharged by said blades in a predetermined direction, said means comprising a rotatable element providing an inwardly facing surface; means for feeding abrasive to said surface; and means for deflecting the abrasive accumulated on said surface into the path of rotation of said abrasive propelling blades.

30 14. In an abrading apparatus, a rotor having a plurality of abrasive propelling blades terminating short of the axis of rotation to define a central abrasive admitting space, abrasive feeding means mounted in said space and rotating synchronously with said rotor providing an inwardly facing abrasive supporting surface, said surface having a discharge edge disposed between the inner ends of said blades, means for depositing abrasive upon said surface, and abrasive deflecting means for deflecting the abrasive deposited on said surface over said discharge edge into the path of rotation of the inner ends of said blades.

35 15. The abrading apparatus set forth in claim 14, wherein said abrasive deflecting means comprises a disc disposed within said abrasive feeding means and mounted for rotation about an axis which is inclined with respect to the axis of rotation of said rotor.

40 16. In an abrading apparatus, a structure mounted for rotation at high speed, said structure providing a generally cylindrical surface facing the axis of rotation of said structure, means for depositing abrasive upon said surface while said structure is rotating, and discharge means for moving said deposited abrasive axially so as to discharge it from one edge of said surface when said abrasive attains a predetermined position in the rotation of said structure, said dis-

charge means comprising a primary deflecting element and a secondary deflecting element for engaging the deposited abrasive, said primary deflecting element having means for adjusting it toward and away from said generally cylindrical surface.

45 17. In an abrading apparatus, a head structure mounted for rotation and providing a generally annular surface facing toward the axis of rotation of said head structure, means for depositing abrasive upon said surface, and control means for causing the deposited abrasive to discharge from said surface at a predetermined point in the rotation of said head at an abrading velocity.

50 18. The apparatus set forth in claim 17, wherein said control means comprises a member rotating about an axis inclined to the axis of said head structure and co-operating with the abrasive deposited on said annular surface.

55 19. In an abrading apparatus, a head structure mounted for rotation and having an annular abrasive accelerating groove facing toward the axis of rotation of said head, means for depositing abrasive in said groove, said head structure also providing a generally annular, inwardly facing surface adjacent said groove and adapted to receive abrasive overflowing from said groove and control means for causing the discharge of abrasive from said annular surface at a predetermined point in the rotation of said head structure.

60 20. In an abrading apparatus, a rotor mounted for rotation at high speed and having a plurality of abrasive propelling blades provided thereon; a generally cylindrical rotating feed chamber mounted adjacent the axis of rotation of said rotor; means for feeding abrasive to said feed chamber for causing it to centrifugally build up to its angle of repose on the inner surface of said feed chamber; and means for deflecting the accumulated abrasive from said feed chamber into the path of said abrasive propelling blades at a predetermined point in the rotation of said rotor, for causing the abrasive to be picked up and discharged by said blades in a predetermined direction.

65 21. In an abrading apparatus, a rotor mounted for rotation at high speed and having a plurality of abrasive propelling blades provided thereon, said blades terminating short of the axis of rotation of said rotor to define a central space; a generally cylindrical feed chamber secured to said rotor, and projecting into said central space, said feed chamber terminating at one end in a discharge edge located adjacent the inner ends of said blades, means for feeding abrasive to said feed chamber, whereby it centrifugally accumulates on the inner wall thereof, and means for deflecting the accumulated abrasive from said feed chamber over the discharge edge thereof and over the inner ends of said blades at a predetermined point in the rotation of said rotor, for causing the abrasive to be picked up and discharged from said blades in a predetermined direction.

70 22. The abrading apparatus defined in claim 21, wherein said rotor comprises at least one disc-like structure and said blades are disposed with their side edges contiguous to one face thereof, and said feed chamber is secured to said structure with its discharge edge located between said structure and a plane normal to the axis of rotation of said rotor and disposed midway between the side edges of said abrasive propelling blades.

75 23. The abrading apparatus defined in claim 21,

wherein the diameter of said feed chamber is approximately equal to the length of said blades.

24. In an abrading apparatus, a structure mounted for rotation at high speed and having a plurality of abrasive propelling blades provided thereon, a rotatable feed chamber mounted adjacent the axis of rotation of said structure and having an inwardly facing surface, means for feeding abrasive to said feed chamber, and deflecting means for deflecting the abrasive accumulated on said surface into the path of rotation of said blades at a predetermined point in the rotation of said structure, said deflecting means being adapted for selective rocking movement about the axis of rotation of said structure into a plurality of different angular positions, whereby the point in the rotation of said structure at which the abrasive is deflected into the path of rotation of said blades may be selectively varied.

25. In an abrading apparatus, a rotor having a plurality of abrasive propelling blades provided thereon; a rotatable element mounted adjacent the axis of rotation of said rotor and providing an inwardly facing abrasive accumulating surface; feeding means for supplying abrasive to said surface; and a rotatable disc for deflecting the abrasive accumulated on said surface in-

to the path of rotation of said abrasive propelling blades at a predetermined point in the rotation of said rotor for causing the abrasive to be picked up and discharged by said blades in a predetermined direction, said disc having a central opening, said feeding means being operable to discharge abrasive into said rotatable element through the central opening of said disc.

26. In an abrading apparatus, a rotor having a plurality of abrasive propelling blades provided thereon, said blades terminating short of the axis of rotation of said rotor to define a central space; said rotor having in said central space an inwardly facing abrasive accumulating annular ledge rotatable synchronously with said rotor and having a discharge edge located adjacent the path of rotation of the inner ends of said blades, and between the planes of rotation defined by the side edges of said blades; means for depositing abrasive upon said ledge, and means for deflecting the accumulated abrasive from said ledge over the discharge edge thereof and onto the inner ends of said blades at a predetermined point in the rotation of said rotor, for causing said abrasive to be discharged in a predetermined direction from said rotor.

WALTER L. KEEFER.
